CLAIM

The ornamental design for an ambidextrous cooking glove, substantially as shown and described.

DESCRIPTION

FIG. 1 is a front elevational view of an ambidextrous cooking glove showing my new design; the rear view being a mirror image thereof;

FIG. 2 is a top plan view thereof;

FIG. 3 is a right side elevational view thereof;

FIG. 4 is a left side elevational view thereof;

FIG. 5 is a bottom plan view thereof; and

FIG. 6 is a front elevational view of a modified form of the glove shown in FIG. 1; the rear view being a mirror image thereof.

FIG. 2

FIG. 1

FIG. 3

FIG. 4

FIG. 5

FIG. 6
